SIGNORS TO JOSEPH A. VOGEL COMPANY, OF WILMINGTON, DELAWARE, A COR-
PORATION OF DELAWARE.

FLUSHING MECHANISM.

Application filed April 5, 1927. Serial No. 181,108.

This invention relates to certain new and useful improvements in flushing mechanism of the type wherein the flushing mechanism is operatively controlled by the pressure of 5 the closet seat, and particularly to that class of flushing mechanism of the stated type in which valves control the flow of water from a supply pipe to a closed tank wherein the contained air is compressed, and from thence to 10 the hopper or bowl for the flushing action.

The invention more particularly relates to a flushing mechanism of the character set forth wherein the flush water is admitted directly to the upper rear portion of the bowl 15 through the medium of a seat-controlled valve mechanism mounted directly upon the bowl.

The primary object of the present invention is to provide a flushing mechanism in 20 which valves are arranged within a casing to which easy access is afforded, and in which the valve mechanism as a whole is so mounted as to permit of its ready and convenient removal for cleaning, repairs and renewal 25 of parts as occasion requires in service.

A further object of the invention is to provide a flushing mechanism which is of maximum simplicity of construction, reliability and efficiency in action, which is comparatively inexpensive of production and installation, which is composed of comparatively few 30 parts, and which dispenses with a valve cage and is devoid of complex stuffing elements or other parts easily subject to wear or liability 35 to clog or get out of order.

A still further object of the invention is to provide a valve operating mechanism which is automatically adjustable or variable in action to compensate for wear of a valve element.

A still further object of the invention is to provide novel means for attaching the seat bracket to the rock shaft of the valve mechanism, which means may be adjustable to vary 45 the throw of the shaft for wear compensating actions.

The invention consists of the features of construction, combination and arrangement of parts, hereinafter fully described and 50 claimed, reference being had to the accompanying drawings, in which:—

Figure 1 is a side elevation showing the application of the flushing mechanism to a bowl and the seat in normal position.

Figure 2 is a top plan view of the bowl and 55 the parts of the flushing mechanism mounted thereon.

Figure 3 is a vertical longitudinal section 60 through the bowl and valve mechanism, showing the seat elevated to move the actuating rocker arm out of the path of the valve stem.

Figure 4 is a similar view showing the 65 parts of the valve mechanism as they appear when the seat is depressed from the normal position shown in Figure 1.

Figure 5 is a vertical transverse section taken substantially on line 5—5 of Figure 4.

Figure 6 is a detail view showing the yielding motion transmitting and compensating 70 means for coaction with and between the valve stem and the actuating rocker arm.

Figure 7 is a longitudinal section through 75 an arm of a seat bracket, showing a modified form of means for securing the bracket to the rock shaft of the valve actuating mechanism.

Figure 8 is a view similar to Figure 7, showing a seat bracket fastening means of adjustable type.

Figure 9 is a view similar to Figure 4 disclosing a modification in the construction of 80 the casing and elements of the valve operating means.

Figure 10 is a sectional view taken on line 85 10—10 of Figure 9.

Referring now more particularly to the drawings, 1 designates a bowl of any ordinary or preferred construction which is provided at its upper rear portion with an extension 2 forming an inlet passage 3 for the flow of the flush water thereto, which passage 3 opens at its inner end into the upper rear portion of the bowl and at its outer end through the top of the extension 2.

Fitted at its lower end within the said 95 opening in the top of the extension 2 is a valve casing 4 having at its lower end an internally threaded aperture within which is fitted the externally threaded upper end of a detachable valve casing discharge and guide 100 extension 5 which opens at its upper end into the bottom of the casing 4 and is provided at its lower end with a guide opening 6 and an annular abutment shoulder 7 and above said shoulder is formed with an annular series of 105 water discharge ports 8 communicating directly with the passage 3. At its said lower end the valve casing is provided with a sup-

porting flange 9 which rests upon a gasket or washer 10 seated upon the top of the extension 2 about the inlet opening of the water passage therein, and forming an air and water-tight connection between the two, said flange and gasket being perforated for the passage of bolts or similar fastenings 11 whereby the valve casing is mounted in position upon the bowl.

- 10 The valve casing is provided at its upper end with externally and internally threaded nipples 12 and 13 which are in direct communication with each other and in communication with the body of the valve casing 15 through a port 14 in a partition 15. The nipple 12 provides a water feed or supply inlet which receives the lower end of the vertical arm of an L-shaped connector, union or fitting 16, provided with an annular flange 17 against which bears a clamping nut 18 engaging the nipple whereby said connector is detachably secured to the valve casing, packing 19 of a suitable kind being introduced between the flange 17 and the nipple to make 20 a water-tight connection. The lower end of the vertical arm of the nipple is formed with a valve seat projection 20, and the free end of the horizontal arm of the connector, which extends rearwardly from the valve casing, is 25 provided with an annular externally threaded coupling head or enlargement 21 to receive a nut 22 which detachably couples said connector with a water feed or supply pipe 23 leading from any suitable source of supply 30 of water under pressure. The nipple 13 receives one end of a section of piping 24 connecting the annular passage 25 at the upper end of the valve casing with the lower end of a closed flush tank 26 which is suitably 35 arranged above and in rear of the bowl. The partition 15 is provided with a valve seat 27 arranged in vertical alinement with the seat projection 20 of the connector 16. A duplex valve 28 is disposed in the passage 40 25 and is movable vertically between the valve seats 20 and 27. This valve is provided at its upper end with a valve member 29 which is winged or peripherally slotted for the flow of air and water about it and between said 45 valve and the walls of the nipple 12, and said valve includes a renewable washer or seat disk 30, of rubber or other resilient or semi-resilient material, adapted to engage the seat projection 20 when said valve is in 50 closed position and thereby cut off communication between the water supply pipe and the tank and the bowl. At its lower end the valve is provided with a valve member 31 of conical form to engage the valve seat 27 55 and control the port 14 for the flow of water between the tank and the bowl.
- The valve 28 is mounted upon the upper end of a rod or stem 32 which extends downwardly through the port 14 and the valve 60 chamber and into the outlet extension 5 and

is provided at its lower end with a guide flange or head 33 which is movable in the guide opening 6, whereby the lower end of the valve stem is accurately guided, the upper end of the stem and the valve 28 being guided by the wings of the valve member 28 within the nipple 12, whereby, in a simple manner, an accurate guiding of the valve and its stem in their motions is obtained.

Formed on or suitably applied to the stem 75 32 at a suitable point above the flange or head 33 is a stationary collar or abutment flange 34, and surrounding the lower end of the stem between the shoulder 7 and this collar or flange 34 is a coiled expansion spring 80 35. This spring operates at all times when the valve stem is relieved from a predetermined downward forcing pressure to hold the seat in the normal or slightly elevated position shown in Figure 1 and to hold the valve in the normal position shown in Figure 3, in which the valve member 29 is closed and the valve member 31 is open. Also mounted on the stem or rod 32 above the collar or flange 34 is a sliding sleeve 36 having a flange 37 85 at its upper end, between which flange 37 and the flange 34 is a coiled expansion spring 38. This spring 38 is shorter and stiffer than the spring 35 and serves to normally hold the sleeve 36 elevated a predetermined distance above the flange or collar 34, as shown in Figure 3.

The body of the valve casing is provided with a forwardly extending seat supporting bracket 39 which is hollowed to form a chambered offset receiving a valve actuating rocker arm 40 having a forked or bifurcated free end 41 to straddle the stem 32 and engage the flange 37 of the sleeve 36, the opposite end of said arm being formed to provide a gear segment 42 which is suitably fixed upon a motion transmitting rock shaft 43 journaled in the side walls of the chambered bracket 39. This gear segment 42 meshes with a gear 44 on the angular or non-circular central portion 45 of a valve actuating rock shaft 46, which is journaled in the side walls of the chambered bracket 39 and has its ends extending outwardly through stuffing boxes 47, which outwardly extending ends of the shaft fit in transverse openings in the free ends of the fork arms 48' of a bifurcated or forked seat carrying bracket 48 and are suitably secured thereto, as by screws 48''. The bracket 48 is suitably fastened to the closet seat 49, which is thus mounted for vertical swinging movements toward and from the bowl with the shaft 46, the latter being thereby rocked to communicate motion through the gear elements 44 and 42 to the valve stem 32. The stuffing boxes 47 are provided with suitable packing 47^a and glands or followers 47^b for an obvious purpose.

As above-described, Figure 3 shows the raised position of the valve, which is its nor-

mal position for cutting off the flow of water from the water supply pipe to the tank, and which is also its position during a flushing action, while Figure 4 shows the depressed position of the valve in which it opens communication between the water supply pipe and tank and closes communication between the tank and bowl. Figure 3 shows, furthermore, the position of the valve when the seat 49 is in the elevated position shown in said figure, as well as in the slightly raised normal position shown in Figure 1, and at all other times except when the seat is depressed to the position shown in Figure 4. In Figure 3 the seat 49 is shown raised from the normal position shown in Figure 1 to a substantially vertical position, to which position it may be raised whenever it is desired to swing the crank arm 40 into the chambered offset 39 and out of the path of the valve stem 32, which movement of the arm 40 is effected by the action of the gears 42 and 44 when the seat is swung to a vertical position. When the arm 40 is thus moved into the chamber 39 and out of the path of the stem 42, the way is clear for an unimpeded removal of the valve stem and attached parts as a unit through the top of the valve casing upon disconnecting the connection 16, thus admitting of the ready and convenient detachment of the valve parts for cleaning, repairs or the substitution of new elements for old ones. When the seat is swung downward from the position shown in Figure 3 to that shown in Figure 1, the apparatus is in readiness for service operation, and in such position of the seat it will be understood that the crank member 40 will rest upon the flange 37 of the sleeve 36 and that the weight of the seat will be supported by the springs 35 and 38, which will be slightly compressed or tensioned, but not to a sufficient degree to cause a downward opening movement of the valve 28.

The tank 26, which is air-tight, and normally contains air under atmospheric pressure, is normally free from any water content. This condition is maintained as long as the seat 49 is in the position shown in Figure 1, or in any other position except that shown in Figure 4, since, except when the seat is depressed to the position shown in Figure 4, the valve member 29 is closed and cuts off the flow of water from the supply pipe or feed pipe 23. When, however, the seat 49 is depressed to the position shown in Figure 4, the arm 40 is swung downward by the action of the gear elements 42 and 44, causing downward motion to be transmitted through the yielding connection 36-38 to the valve stem 32, whereby the valve 28 is depressed, so as to establish communication between the pipe 23 and the tank 26 via the pipe 24 and close communication between both the pipe 23 and the tank and the bowl. Water under service pressure will thereupon flow from the pipe 23

to the tank 26 and will continue to flow as long as the seat 49 is held depressed, until the contained body of air in the tank 26 is compressed to a pressure equaling that of the water service pressure, whereupon the flow of water to the tank will be automatically arrested irrespective of the position of the valve, the apparatus being now prepared for a full flushing action. When, therefore, the seat 49 is released, the springs 35 and 38 react and shift the arm 40 upwardly, thereby, through the action of gears 42-44, raising the seat to the normal position shown in Figure 1, and at the same time elevating the valve from the position shown in Figure 4 to that shown in Figure 3. Valve member 29 will thus be caused to positively cut off any inflow of water from the pipe 23, while valve 31 will be opened for the flushing action, the water being forced from the tank 26 by the action of the compressed air through the valve casing and into the bowl. Upon the emptying of the tank 26 normal conditions will be restored for a repetition of the tank refilling and flushing actions upon the seat 49 being thereafter depressed and subsequently released.

The sleeve 36 and its spring 38 in connection with the collar or flange 34 of the stem 32 provide a yielding motion transmitting means or connection for transmitting motion from the crank arm 40 to the valve stem when said crank arm is actuated by the depression of the seat 49. These parts 34, 36, 37 and 38 also provide a compensating means or device which allows the valve stem to have such varying degrees of downward motion as may be necessary to compensate for wear upon the valve 31. It will be evident, of course, that the spring 35 is of such length, strength and range of expansion that it will under all conditions, except when the valve stem is forcibly depressed by downward movement of the seat to a horizontal position, keep the valve 29 tightly closed against its seat 20, but that as valve 31 progressively wears from use the range of downward movement of the valve stem must be progressively increased. This progressive increase in downward motion of the valve stem is secured by a compensating action of parts 34, 36 and 38. Normally, that is, when the valve 31 is new or unworn, the parts are so relatively arranged and coact that on a working movement of crank arm 40 a short range of downward movement of the stem 32 will be sufficient to close valve 31 in which spring 35 will be compressed to a certain degree, sufficient to close valve 31, during a part of the movement of crank arm 40, and the remainder of the movement of crank arm 40 will be permitted by compression of spring 38. As wear upon the valve 31 occurs and increases, however, a greater downward range of movement of stem 32 under the same degree of throw of crank arm

40 is required, which is obtained by the variations of motion allowed by linear variations of the stiff spring 38. An automatic adjustment of the valve itself is thus provided for, 6 to effect a positive water feed cut off action at cut off periods as long as the valve 31 is in serviceable condition, thus avoiding the necessity of frequent replacements of valve 31 or manual compensating adjustments 10 from time to time, in order to secure a positive cut off action and to prevent leakage, which would otherwise be required. The parts 36 and 38 further provide a shock absorbing or cushioning connection between the 15 valve actuating means and the valve to prevent any possibility of injury to the valve mechanism from shocks or jars occasioned, for example, by the accidental dropping of the seat 49 from its maximum raised position shown in Figure 3 to its service position 20 shown in Figure 1, as will be readily understood.

In Figure 7 we have shown a different 25 mode from that previously described of connecting the seat supporting bracket with the valve actuating rock shaft. As shown in Figure 7, the seat supporting bracket 48^a has each of its fork arms formed to provide a 30 U-shaped yoke 48^b, the yokes of the crank arms being adapted to be slipped from above down upon the ends of the valve actuating 35 shaft 45^a, each yoke and the portion of the shaft which it engages being apertured for the passage of a fastening screw 48^c, the construction being such as to adapt these parts to be readily and conveniently connected and disconnected.

In Figure 8 we have shown still another 40 mode of connecting the seat supporting bracket 48^a with the valve actuating shaft in which each arm 48^e of the bracket is transversely slotted, one end of the slotted portion forming a journal receiving a sleeve upon an adjusting arm 48^f, which is fastened 45 to the valve actuating shaft 45^b by a pin or other suitable fastening member 48^g. The arm 48^e has a threaded opening receiving an adjusting screw 48^h bearing on the bottom wall of the slot and the head of which is accessible 50 from the outer side of the slot to permit adjustment of said screw, whereby the seat supporting bracket may be tiltably adjusted with relation to the shaft 45^b to vary the normal working position of the seat with regard 55 to the bowl within certain degrees. The top wall of the slot in the arm is provided with a threaded opening to receive a set screw or lock screw 48ⁱ which may be adjusted to bind 60 against the head of the screw to hold it from upward movement and from retrograde rotation. By means of this adjustable fastening connection the position of the seat may also be varied to regulate its degree of downward operative movement and consequently 65 the operative movement of lever 40 to com-

pensate for variations in the degrees of movement of the valve to effect a sealing engagement between the valve 31 and its seat 14, which construction may be used in addition to or in lieu of the motion compensating 70 means 34, 36, 37 and 38, if desired.

In Figures 9 and 10 we have shown a modified construction which dispenses with the use of parts 42, 43 and 44, and in which the transverse shaft 46 is mounted upon the valve casing in rear of the valve stem and the crank arm 40 projects forwardly for engagement with the flange 37 of sleeve 36. This requires the use of a seat supporting 75 bracket with fork arms of some considerable length to reach the required distance and to clear the casing to permit the seat to be swung upwardly to a vertical position. Also if these fork arms were made continuous, an objectionable backward movement of the crank 80 arm 40 would be required on such movement of the seat, and in making the bracket and long arms in a single casting the arms might 85 be objectionably weak. These objections are overcome by dividing the arms into sections or providing the bracket 48^e with short arms 50 pivotally coupled by a bolt 51 with arms 52 fastened to the shaft 46, on the angular part of which, in this instance, the crank arm 40 is directly mounted. The arms 90 are formed with hinge knuckles for the bolt which are located adjacent to the upper edges of the arms, which are provided below the hinge knuckles with shoulders or abutment surfaces 53 adapted to abut when the arms 95 are in longitudinal alinement. The bolt 51 is movable in slotted guides 54 at the front of the valve casing, whereby upward movement of the bolt and arms 50 is limited. When the parts are in normal working position 100 the shoulders 53 abut, thus making the arms rigid for valve actuating motion under depression of the seat. The seat may, however, be swung upward to a substantially vertical position on the bolt 51 as an axis, carrying with it the bolt up the limit of the upper ends of the slots in the guides 54, thus 105 moving arms 52 upward and rocking shaft 45 sufficiently to swing arm 40 to a retracted position out of the path of the valve, as will be readily understood. This construction 110 provides a working connection of considerable strength between the seat bracket and rock shaft which dispenses with the use of gearing, and one which allows upward movement of the seat to a full vertical position 115 without an undue backward movement of the crank arm 40.

It will be seen from the foregoing 120 description that our invention provides a flush valve mechanism which may be mounted vertically directly upon the upper rear portion of the bowl, and which may be connected in a simple and convenient manner with a water supply pipe and flush tank for working ac- 125 130

tions, and it will also be seen that a very simple type of valve mechanism, devoid of cages or complex parts, is provided, whereby the use of parts requiring frequent adjustments, repairs or renewals is dispensed with. By simply raising the seat so as to swing the crank arm 40 out of the path of the collar 37 and uncoupling and detaching the connector or union 16, full and complete access 10 to the valve casing may be obtained for the removal of the valve elements as a unit, for cleaning, repairs or replacements of gasket 30 or other parts whenever required in service. The yielding motion transmitting and 15 compensating connection formed by the parts 34, 36, 37 and 38 ensures an easy transmission of motion to the valve stem, with entire elimination or material reduction of shocks or jars, so that damage to these working parts, even when the seat is roughly handled, will be prevented, while the compensating action ensures a positive working connection at all times between the actuating crank arm and the valve while permitting 20 automatic adjustment of the valve for a positive closing movement of valve member 31 as long as said valve member is in condition for use. As the valve device in the main consists of parts not liable to be easily injured or quickly worn, the gasket 30 being 25 the only part subject to material wear and required to be renewed at intervals, it is evident that a valve mechanism capable of long service without repairs, renewals or adjustments is provided by the construction employed.

Other advantages of the invention will be understood and appreciated by those versed in the art without a further and extended description.

Having thus fully described our invention, we claim:—

1. In a flushing apparatus, a bowl, a valve casing extending vertically above the bowl and communicating at its lower end therewith, a valve device in said casing for controlling the flow of water from the casing to the bowl, a valve actuating rocker arm mounted in said casing, a rock shaft journaled in the casing, gearing between said rock shaft and rocker arm, and an actuating element connected to said rock shaft for imparting valve controlling movements through said gearing to the rocker arm.

2. In a flushing apparatus, a bowl, a valve casing having a water supply inlet and a water discharge outlet, the latter communicating with the bowl, a valve in said casing movable to open and close said inlet, a spring 55 for normally holding said valve opening with respect to said inlet, a resilient motion transmitting and compensating means connected with the valve, a pivotally mounted actuating element engageable with said means for transmitting valve closing pressure thereto in op-

position to the valve opening pressure of the spring, and means for operating said element.

3. In a flushing apparatus, a bowl, a valve casing having a water supply inlet and a discharge outlet, the latter communicating with the bowl, a valve movable to open and close said inlet, a stem connected with said valve, a spring acting on the stem for normally holding the valve open, a resilient motion transmitting and compensating element connected 70 with the stem, and an actuating device engageable with said element for imparting valve closing motion to the stem in opposition to the pressure of the spring.

4. In a flushing apparatus, a bowl, a valve casing having a water supply inlet and a water discharge outlet, the latter communicating with the bowl, a stem movable in said casing, a valve carried by said stem and movable thereby to open and close said water supply inlet, an abutment on the stem, a spring acting on said abutment for normally holding the valve closed, a sliding pressure transmitting member on the stem, a spring between said member and said abutment, and 80 an actuating device engageable with said member for transmitting motion through the second-named spring to the stem for opening the valve in opposition to the pressure of the first-named spring. 95

5. In a flushing apparatus, a bowl, a valve casing rising vertically from the bowl and having at its lower end a water discharge outlet communicating with the bowl, said casing having at its upper end an inlet port, 100 a water supply port and a combined water outflow and inflow passage for connection with a pressure tank, a vertically movable valve stem in the valve casing, a valve carried by said stem and movable in opposite 105 directions to alternately close the inlet and water supply ports with respect to said outflow and inflow passage, an abutment on the stem, a spring acting on said abutment for normally holding the valve in position to 110 close the water supply port, a sliding motion transmitting member on the stem, a spring between said member and said abutment, and an actuating element engageable with said motion transmitting member for transmitting motion to the second-named spring to 115 shift the valve to open the water supply port and close the inlet port against the opposition of the first-named spring.

6. In a flushing apparatus, a bowl, a valve casing rising vertically from the bowl and having a water discharge outlet at its lower end communicating with the bowl, said casing having at its upper end an inlet port for admission of flush water thereto from a storage tank, a water supply port for connection with a water supply pipe and a combined outflow and inflow passage for connection with the tank, and said casing having a forwardly projecting chambered offset portion 125 130

intermediate of its ends, a valve stem movable vertically in the casing, a valve carried by said stem and movable thereby in opposite directions to alternately open and close the inlet port and water supply port with respect to the outflow and inflow passage, spring means acting on the valve for normally holding it in position to close the water supply port, a rock shaft journaled in the chambered offset portion of the valve casing, an actuating rocker arm mounted in said chambered offset portion of the valve casing and movable to transmit motion to the valve stem in opposition to the spring, gearing between said rock shaft and rocker arm, and a seat connected with the rock shaft.

7. In a flushing apparatus, a bowl, a valve casing having a water inlet port and a discharge port, the latter communicating with the bowl, a valve movable to open and close the water inlet port, a spring for normally holding said valve open with respect to said water inlet port, an actuating element, and a yielding motion transmitting and compensating element engageable by said actuating element for variably transmitting closing motion to the valve in opposition to said spring.

8. In a flushing apparatus, a valve casing having a water inlet port, a valve movable in opposite directions to open and close said port, a spring acting on the valve to force it open, a valve actuating member, and a yielding motion transmitting and compensating means adapted to be engaged by the valve actuating member to transmit a greater or less degree of movement to the valve for a closing action in opposition to the said valve opening spring.

9. In a flushing apparatus, a valve casing having a water inlet port, a valve stem, a valve carried by said stem and movable in opposite directions to open and close said port, a spring acting on the stem to force the valve open, an abutment on the stem, a second spring engaging said abutment, a sliding element on the stem for compressing the latter-named spring, and a seat controlled actuating device engageable with said element to apply a valve closing movement to the stem through the second-named spring against the opposition of the first-named spring.

10. In a flushing apparatus, a valve casing having an outlet at its lower end for communication with a bowl and having at its upper end a primary water intake port, a passage for connecting said port with a storage tank and a secondary intake port for connecting said passage with the body of the valve casing, a water supply connection detachably coupled to the upper end of the casing and communicating with the primary intake port, a valve device comprising a valve stem disposed within the body of the casing

and extending through said secondary intake port into the passage and valve members on said stem and in said passage for alternately opening and closing said intake ports, means for normally holding the valve device in position to close the primary intake port, means within the casing between the secondary intake port and discharge port and engageable therein with the stem to adjust the valve device to open the primary intake port and close the secondary intake port against the opposition of the first-named means, and seat controlled means for actuating the second-named means.

11. In a flushing apparatus, a bowl, a valve casing having a discharge outlet communicating with the bowl and having a water supply inlet, a spring-closed valve in said casing controlling said inlet, a pressure spring in engagement with the valve, actuating means in the casing for transmitting motion through said pressure spring to the valve in opposition to its closing spring, and an actuating element coupled to said actuating means.

12. In a flushing apparatus, a bowl, a valve casing extending vertically above the bowl and having an outlet at its lower end communicating with the bowl, said casing having at its upper end a passage for flow of water to and from a storage tank, a primary intake port at the top of said passage for connecting the same with a water supply pipe, and a second intake port connecting the bottom of said passage with the upper portion of the valve casing, a valve in said casing comprising a stem disposed in the body of the casing and carrying upper and lower valve members located in said passage and movable toward and from the primary and secondary intake ports for alternately opening and closing said ports with respect to the passage, spring means for normally maintaining the valve in position to cause the upper valve member to close the primary intake port and the lower member to open the secondary intake port, actuating means in the valve casing for moving the valve in the direction to cause the upper valve member to open the primary intake port and the lower valve member to close the secondary intake port, and a seat operatively coupled to the said valve actuating means.

13. In a flushing apparatus, a bowl, a valve casing having a water inlet port and a water discharge port, the latter communicating with the bowl, a valve movable to open and close the water inlet port, a spring for normally holding said valve in open position with respect to said inlet port, a seat-operated valve-actuating element, and a resilient transmission means arranged between the valve and said element and adapted to be engaged by said element for yieldingly transmitting closing movement to the valve with

respect to said inlet port in opposition to the valve opening pressure of the valve opening spring.

14. In a flushing apparatus, a bowl, a duplex valve movable in one direction to open communication between a water supply pipe and a tank and to close communication between the pipe and the bowl, and movable in a different direction to close communication between the pipe and the tank and to open communication between the tank and the bowl, a spring for normally moving the valve

in the second-named direction, a seat, a pressure spring connected to the valve, and a rocker arm actuatable by the seat for yieldingly transmitting motion through said pressure spring to the valve in the first-named direction in opposition to the first-named spring. 15

In testimony whereof we affix our signatures. 20

JOSEPH A. VOGEL.
ARTHUR J. JENNINGS.
